FIG. 1

FIG. 2

FIGURE 1 is a perspective view of a combined bed, chest of drawers and diaper changing support with the diaper support in open position and wherein the sides and rear of the bed portion are formed of open railings.

FIGURE 2 is a perspective view of the article of FIGURE 1 but wherein the sides and rear peripheral walls of the bed portions are solid panels.

The sides and ends not shown are conventionally plain and unornamented.

I claim:

The ornamental design for a combined bed, chest of drawers and diaper changing support, substantially as shown and described.
